DESIGN FOR A COMBINED SHIPPING AND DISPLAY BOX

John A. Clemens, Providence, R. I., assignor to Davol Rubber Company, a corporation of Rhode Island

Application December 7, 1938, Serial No. 81,615

Term of patent 14 years

To all whom it may concern:

Be it known that I, John A. Clemens, a citizen of the United States, residing at Providence, in the county of Providence and State of Rhode Island, have invented a new, original, and ornamental Design for a Combined Shipping and Display Box, of which the following is a specification, reference being had to the accompanying drawing, forming part thereof.

In the drawing:

Fig. 1 is a perspective view of a combined shipping and display box, showing my new design;

Fig. 2 is a perspective view of the same in open position, one end being shown partially broken away;

Fig. 3 is a perspective view of the compartment forming insert thereof forming a part of the unitary design shown in Figs. 1 and 2; and

Fig. 4 is a perspective view of the retaining insert thereof forming a part of the unitary design shown in Figs. 1 and 2.

I claim:

The ornamental design for a combined shipping and display box, substantially as shown and described.

JOHN A. CLEMENS.
